UNITED STATES PATENT OFFICE.

ANTHONY J. SCHINDLER, OF BLOOMFIELD, NEW JERSEY.

CONTAINER.

Application filed October 19, 1920. Serial No. 417,954.

To all whom it may concern:

Be it known that I, ANTHONY J. SCHINDLER, citizen of the United States, residing at Bloomfield, in the county of Essex and State 5 of New Jersey, have invented new and useful Improvements in Containers, of which the following is a specification.

This invention relates to improvements in spouts for pasteboard and like boxes and 10 cartons, and one of the principal objects is to provide a device of this nature which may be stamped at the same time and from the same sheet that the box blank is stamped from.

15 Another object is to provide a device of this nature which shall be simple in structure, cheap of manufacture, and efficient for the purpose for which it is designed.

With these and incidental objects in view, 20 the invention consists in certain novel construction which is hereinafter fully described and claimed and which is shown in the accompanying drawing comprising one sheet, in which:—

25 Figure 1 is a plan view of the end of a carton blank embodying my invention.

Figure 2 is a similar view illustrating another embodiment of my invention.

Figure 3 is a perspective view of the form 30 shown in Figure 1 with the spout open.

Figure 4 is a similar view of the embodiment shown in Figure 2.

This invention contemplates providing a 35 paste board or like carton for use as a container for cereals and like material, with perforated and creased portions which normally form shutters and which may be folded outwardly to form a spout for directing the discharge of the material and may 40 then be folded back to their normal position to seal the package against dust and dirt.

Referring more particularly to the drawing, 1 represents the end portion of a carton 45 which is cut down on lines 2, 3 and 4 so as to form front and rear flaps 5 and 6, and right and left side flaps 7 and 8.

In the form shown in Figures 1 and 3, the 50 rear flap 6 is provided with an aperture 9, and the front flap 5 is perforated on lines 10, 11 and 12 and creased on lines 13 and 14 so as to form two shutters 15 and 16. The right-hand side flap 7 is left intact, and the 55 left-hand side flap 8 is cut on lines 17 and 18 and creased on lines 19 and 20 to form shutters 21 and 22.

When the carton is sealed, the side flaps 7 and 8 are first folded over, then the back flap 6 is folded over and glued to flaps 7 and 8 with aperture 9 registering with shutters 60 21 and 22, and finally the front flap 5 is folded over and glued to flap 6 with the shutters 15 and 16 in register with aperture 9. This aperture 9 is somewhat larger than the space defined by the shutters so as to 65 prevent the gluing down of the shutters. To open the carton, a pen knife is run along lines 10, 11 and 12 and shutters 15 and 16 are folded back on hinge lines 13 and 14. Shutters 21 and 22 are then folded out on 70 hinge lines 19 and 20 so that a spout is formed by shutters 15, 16, 21 and 22 as shown in Figure 3, members 15 and 16 pressing against 21 and 22 to hold the spout tight in formation.

75 In the modified form shown in Figures 2 and 4, an aperture 23 is formed in the free edge of the back flap 6, and the front flap 5 is perforated on lines 24, 25 and 26 and creased on lines 27 and 28 to form shutters 80 29 and 30, the crease 28 being co-incident with the hinge crease of flap 5. Side flap 7 is cut on line 31 and creased on line 32 to form a shutter 33; and flap 8 is cut on line 34 and creased on line 35 to form a shutter 36.

In sealing this form of package, the flaps are folded over and glued as in the form first described, and in opening, the lines 24, 25 and 26 are cut with a knife and 90 the flaps 29, 30, 33 and 36 are folded out to form the spout as shown in Figure 4.

It is obvious that the shutters may be located in various portions of the flaps as desired, and that other parts may be varied 95 without in any way departing from the spirit of my invention. I, therefore, do not limit myself to the exact details of construction set forth herein, nor to anything less than the whole of my invention limited only 100 by the appended claims.

What I claim as new and desire to secure by Letters Patent is:—

1. A carton comprising end flaps formed with shutters adapted to be folded outwardly to form a spout for directing the flow of the contents from said carton irrespective of which edge of the end of the carton is in lowered position.

2. A carton comprising end flaps formed with shutters adapted to be superposed when said carton is sealed and to be moved

- to a position to form a spout for directing the flow of the contents from said carton and completely enclosing the contents as it passes from the carton.
- 5 3. A carton comprising flaps formed with shutters and a flap adapted to be interposed between said shutter containing flaps and provided with an aperture registering with said shutters for permitting egress of the 10 contents of said carton and for preventing gluing of the shutter.
4. A carton comprising flaps each provided with a plurality of shutters disposed to open in respective directions for forming 15 a tubular spout to direct the dispensing of the contents of said carton.
5. A carton comprising flaps each provided with a plurality of shutters disposed to open in respective directions for forming 20 a spout to direct the dispensing of the con-

tents of said carton, and also comprising a flap adapted to be interposed between the first said flaps and formed with an aperture to register with said shutters.

6. A carton having one of its walls formed 25 with intersecting lines of perforations and creased so as to define a shutter movable to a position to form part of a tubular spout for aiding in the dispensing of the contents 30 of said carton.

7. A carton having one of its walls provided with a plurality of lines of perforations and creases so as to define a plurality of shutters which may be moved to positions to aid in the dispensing of the contents of 35 said carton and operable to hold one another in such position when moved thereto.

In testimony whereof I have affixed my signature.

ANTHONY J. SCHINDLER.
